SANDING MACHINE

Perley T. Blood, Hamilton, Mont., assignor of
one-half to William A. Bower, Hamilton, Mont.

Application October 27, 1939, Serial No. 301,627

5 Claims. (Cl. 51—170)

My present invention relates to an improved sanding machine of the portable type in which is employed a rotary disc driven by a power-rotor unit such as an electric motor or an air motor. Such devices are usually used for finishing all types of wood surfaces. It has been an inherent objection to most of the sanders that have been on the market or in use in the past that they are not adjustable as to the depth of the finishing or sanding cut which the rotary disc could take upon operation.

Another difficulty with the present portable sanders, if they were adjustable, has been in the complexity in the parts arranged to provide for adjustment.

The principal objects of this invention are to provide a compact portable and motor-driven tool of this character that is simple in construction and operation; to provide a sanding machine composed of the minimum number of parts that are arranged compactly into a unitary structure; to provide a sanding machine having means for adjusting the rotary disc which means are so located as to be available to the operator and so constructed as to provide adjustment without the necessity of special tools or the like; and to provide a sander which can be easily adapted to use in restricted areas such as vertical edges whereby the sanding operation may be carried out fully to the juncture of the surface being sanded with that of an angularly disposed surface.

In my present invention I illustrate a power-rotor unit comprising an electric motor suitably supported upon a base structure and having a rotary disc mounted directly upon the shaft of the power-rotor unit, and means are provided whereby the casing enclosing the rotary disc may be adjusted with relation to the disc for sanding in depressions and the like. I also employ an improved base structure having guide means to insure the finishing of wood surfaces upon an absolutely true plane.

The invention consists in certain novel combinations and arrangements of parts which accompany the foregoing objects and will be more fully set forth hereafter and claimed in the accompanying drawings, wherein I have illustrated a preferred form of my invention and wherein the parts are combined and arranged in accord with the best mode I have thus far devised for the practical application of the principles of my invention.

Figure 1 is a perspective view of the sander illustrating the general arrangement of parts,

Figure 2 is a perspective view of the sander from an angle at variance to that of Figure 1.

Figure 3 is a plan view of the base or housing of my sander.

5 Figure 4 is a perspective view of the lower portion of the sander taken from an angle similar to that of Figure 1 with the removable edging plate partially displaced and portions broken away for convenience of illustration.

10 Figure 5 is a vertical sectional detail view taken transversely through the upper portion of the machine.

Figure 6 is a vertical sectional detail view taken transversely through the base or housing and 15 illustrating the general arrangement of the working parts of the sander.

Figure 7 is a fragmentary vertical sectional view through one edge of the housing and illustrating a manner in which the relation of the 20 parts may be altered under certain circumstances.

Figure 8 is a perspective view of the latch-bar used in connection with my invention.

Figure 9 is a perspective view of the latch-bushing employed in the base housing in securing 25 the removable edging plate, and

Figure 10 is a detail sectional view of the adjustable bearing nut which I employ in connection with my invention.

In the accompanying drawings, wherein like 30 reference numerals refer to like parts throughout the same, the numeral 11 designates a hollow base or housing having an exhaust extension 12 in the interior of which is formed an exhaust passage 13 and a base extension 14 used to guide 35 the sander when the rotary disc is extended over an edge and for other purposes. The main portion of the base is substantially circular in shape and includes a sander-chamber 15 and a blower-chamber 16, divided by means of an inner flange 17, and the exhaust passage 13 communicates with the chamber 16. A passage 18 in the flange 17 communicates between the chambers 15 and 16.

45 A removable edging-plate 19, roughly segmental in shape, is fitted to the forward portion of the base 11 and a lock-stud 20, having a notch 21, engages the bushing 22 of Figure 9, and the notch 21 aligns with a slot 23 in said bushing. The bushing 22 extends laterally through wall 24 of the housing and in a passage 25 I provide the latch-bar 26 of Figure 8, having a flange 27 on its upper end and a slot 28 formed in its lower portion. The bushing 22 passes through the slot 28 and the latch-bar travels up and down with 50 relation to said bushing. The spring-receiving

boss 29 of the lower end of the latch-bar seats against the spring 30 in the lower end of the passage 25 to keep the latch-bar normally raised to its upper position.

A motor case 31 is mounted upon the base 11 and is secured in place by means of screws or bolts 32, with an annular cushion 33 placed between the two parts. A stud-bolt 34 in the base 11 passes through an opening 35 in the motor case 31, as well as through the annular cushion 33, and a knurled adjusting nut 36 is threadably engaged on the upper end of the bolt 34.

The motor case 31 has a hand knob 37 protruding from one face thereof in a position to be conveniently grasped by the left hand of the operator of the portable sander. A conventional hand grip 38 is secured to another portion of the case in the usual manner. In the upper face of the handle 38 I mount the switch 39 and from the lower part of the handle extends the electric conduit cord 40, attached by means of a plug 41.

The motor case 31 is bell-shaped and forms the head 42. Within the interior of the case 31 I mount stationary fields 43 and 44. By means of a suitable bearing (not shown) in the lower portion of the case and the bearing 45 in the head 42 I mount for rotation the armature shaft 46, which has the usual armature 47 and the usual commutator ring 48. Conventional brush-holders are indicated at 49 and brushes 50 are mounted therein for operation upon the commutator 48. Adjustment screws 51 are threaded into the brush-holders 49 for applying pressure to the brushes 50. The brushes are electrically connected to the switch 39 in the conventional manner.

Upon the lower portion of the shaft 46 I fasten the fan hub, or blower 52, which has an annular flange 53 and depending fan blades 54. At 55 the shaft 46 is threaded both interiorly and exteriorly. Upon the exterior threads is engaged the boss 56 of the rotary sander disc 57. A sander cushion 58 is secured to the lower working face of the disc 57 and an abrading disc 59 is fitted to the face of the cushion and secured in place by means of the flat screw 60, which engages the inner threads of the shaft portion 55.

The upper end of the armature shaft 46 is reduced in size at 61 and a bearing-race 62 is fitted thereover and abuts the shoulder formed at the juncture of the shaft 61 near the shaft 46. A bearing ring 63 is mounted for rotation upon the race 62. The head 42 of the motor case has an extension collar 64 which is interiorly threaded for the reception of the adjustable bearing nut 65.

The bearing nut 65 is threaded around its exterior periphery and has an inner web through which is formed a passage 67. In the lower face of the web I form a bearing-race 68, and in the upper face a similar bearing-race 69. The nut has a flange 70 with notches 71 in the under face thereof. The nut 65 is threaded into the extension 64 so that the race 68 will contact the bearing ring 63.

A second bearing ring 71 was placed in the upper race 69 of the nut and the bearing anchor nut 72 having a race 73 is threaded onto the shaft extension 61 and a spacer bushing 74 is fitted into the passage 67 to accurately space the elements 68 and 71.

In a hole 75 in the case extension 64 I fit the spring 76, which acts upon the pin 77 to urge it upwardly and the pin 77 operates in the notches

71 to hold the adjustable bearing nut in an adjusted position.

To the flanges 70 of the nut 65 I secure the adjusting cap 78, which has a knurled or roughened depending skirt 79 encircling the extension 64 of the lower case.

In line with the exhaust passage 13 of the base extension 12 I mount the riser tube 80 having an attaching flange 81 and upon the upper end of the riser tube 80 is a nipple 82 to which is attached the dust-bag 83 for the collection of the dust particles from the material being sanded.

In the lower face of the base or housing and of the removable edging plate I form venting grooves 84, which extend radially from the lower inner edge of the sander chamber 15 and serve to permit the inward flow of air, which will pick up any dust upon the surface on which the sander is being operated, in order that the dust may be conveyed by means of the fan to the dust bag.

In the base extension I form vent holes 85 connected by means of interior vent passages 86, that likewise communicate with the sander chamber for the conveyance of sander dust and the like in a similar manner as before described.

In operation my portable sander is placed upon the surface to be finished and by means of the switch 39 the motor is energized in the usual manner, causing the rotary sander disc to revolve at a high speed. As the disc revolves over the surface, the abrading materials on the face of the disc 59 cut the wood surface or the finish and the simultaneous rotation of the fan blades 54 creates a suction in the chamber 16 which picks up these particles through the vent grooves 84 and the vent holes 85 and exhausts them into the passage 13, through the riser tube 80, from whence they are eventually deposited in the dust bag 83.

If it be desired that more pressure be applied upon the rotary disc 57, a turn of the bearing adjustment nut 65 causes the armature shaft 46 to be extruded downwardly and thus lowers the operating face of the disc 57 with relation to the gliding face of the base 11. A reversal of this operation will result in raising the sander disc from the surface being sanded and a thinner or lighter cut would thereby be taken.

When it is desired to operate the sander closely against a surface disposed at an angle to the surface being sanded, the removable edging plate 19 is disengaged from the housing 11 and the sander can then be operated to within a small fraction of an inch to the edge of the work being finished. To remove the plate 19 the pressure is applied upon the flange 27 of the latch bearing 26, thus depressing it and disengaging the lower edge of the slot 28 from the notch 21 in the stud 20 which may then be withdrawn from the bushing 22. To resecure the plate 19 to the base 11, the pin 20 is inserted into the bushing 22 so that the latch may again engage in the notch 21.

Under certain circumstances it is highly desirable to have only a portion or one edge of the rotary sander disc extrude from the casing, and in order to accomplish this, at one portion of the annular compressible cushion, I compress the material of the cushion by tightening the nut 36 on the stud-bolt 34. This raises the base 11 and the plate 19 substantially, as shown in Figure 7. With the device adjusted in this manner the rotary sanding disc may be operated into depressions as, for example, seat bottoms or into other cupped areas.

It is to be understood that the form of my invention, herewith shown and described, is to be taken as a preferred example of the same, and that various changes in the shape, size and arrangement of parts may be resorted to, without departing from the spirit of my invention, or the scope of the subjoined claims.

Having thus fully described my invention, what I claim as new and desire to secure by Letters Patent is:

1. A portable sander comprising a base housing having a sander chamber having a single opening for the reception of a sander member and adapted to completely enclose such a member and a blower chamber in communication with each other, said blower chamber having a discharge passage; an encased power rotor unit mounted vertically on the base housing and including a drive shaft; a bladed fan on said shaft in said blower chamber; a sander disc in said sander chamber and closing the opening therein; longitudinally adjustable means for said rotor unit comprising an adjustable bearing nut threaded in the casing of the rotor unit, bearing rings cooperating with said nut, and means on said shaft and operating on said bearing rings to rotatably mount the rotor drive shaft in said adjustable bearing nut.

2. A portable sander comprising a base housing having a sander chamber and a blower chamber in communication with each other, said blower chamber having a discharge passage; an encased power rotor unit mounted vertically on the base housing and including a drive shaft; a resilient cushion between said base and said power unit; means including a stud bolt and an adjustment nut cooperable with said bolt for tilting said encased power rotor unit with relation to said base housing; a bladed fan on said shaft in said blower chamber; a sander disc in said sander chamber; longitudinally adjustable means for said rotor

unit comprising an adjustable bearing nut threaded in the casing of the rotor unit, bearing rings cooperating with said nut, and means on said shaft and operating on said bearing rings to rotatably mount the rotor drive shaft in said adjustable bearing nut.

3. In a portable sander of the type employing a chambered base enclosing sander means and blower means and supporting an encased vertically positioned power rotor unit, a segmental edging-plate disposed against an outer face of said chambered base and having an inwardly protruding notched lock-stud, a slotted bushing positioned in the wall of the chambered base to receive the lock-stud, and a latch bar cooperable with the slotted bushing and with the notched lock-stud to retain the edging-plate in position against the chambered base.

4. In a portable sander of the type employing a chambered base enclosing sander means and blower means and supporting an encased vertically positioned power rotor unit, a segmental edging-plate disposed against an outer face of said chambered base and having an inwardly protruding notched lock-stud, a slotted bushing positioned in the wall of the chambered base to receive the lock-stud, and a spring pressed vertically movable latch bar cooperable with the slotted bushing and with the notched lock-stud to retain the edging-plate in position against the chambered base.

5. In a portable sander of the type employing a chambered base enclosing sander means and blower means and supporting an encased vertically positioned power rotor unit, a resilient cushion between said base and said power rotor unit, and means including a stud bolt and an adjustment nut thereon for tilting said encased power rotor unit with relation to said base housing.

PERLEY T. BLOOD.
